Primary Examiner — Michelle E. Wilson*Assistant Examiner* — Sanjeev Paul(74) *Attorney, Agent, or Firm* — Culhane Meadows PLLC; Stephen J. Weed(57) **CLAIM**

The ornamental design for eyewear, as shown and described.

DESCRIPTION

FIG. 1 is a front perspective view of eyewear;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken line showing of the eyewear is for the purpose of illustrating portions of the article and forms no part of the claimed design.
